TUMBLER CYLINDER DRIVE AND SUPPORT STRUCTURE

Alexander L. Reiter, South Bend, Ind., assignor
to Bendix Home Appliances, Inc., South Bend,
Ind., a corporation of Delaware

Application March 28, 1946, Serial No. 657,717

1 Claim. (Cl. 259—81)

1

This invention relates to driving and support structure for tumbler type clothes dryer or other device using a cylinder mounted for rotation on a substantially horizontal axis.

It is a primary object of the present invention to provide means for supporting and for driving a dryer cylinder from the front thereof through a belt drive around the tubular extension of the cylinder which also forms the access opening into the cylinder and to so arrange such drive that the cylinder is supported on rollers through the belt the belt running over the supporting rollers under the tubular extension member between said member and the rollers.

The above and other objects of the invention will be apparent on consideration of the following more detailed description and by reference to the accompanying drawings forming a part hereof and wherein.

Figure 1 is a front view of the assembled dryer showing the drive mechanism and the opening for receiving the clothes, the front panel of the machine being removed.

Figure 2 is a side view partly in section showing the several parts of the dryer including the driving and support mechanism.

Figure 3 is a section on the line 3—3 of Figure 1 and shows the section through the support roller, the belt and tubular extension member of the cylinder.

Referring to the drawings, a base 10 supports a sheet metal rear supporting panel 11 and a front supporting and dividing panel 12 spaced as shown in Figure 2. The front panel 12 has a circular opening 13 provided therein and the rear panel 11 supports a bearing 14. The cylindrical shaped casing 15 is formed in the shape of a flanged tube and its flanges are secured to the inside faces of the rear panel 11 and the front panel 12 respectively. A rotatable clothes containing cylinder 17 has a diameter slightly less than the cylindrical shaped casing 15 and is of a length slightly less than the distance between the front panel 12 and the rear panel 11. A short shaft 18 is secured to the back wall of the rotatable cylinder 17 and this shaft is supported in a bearing 14. The clothes cylinder 17, as more completely described in co-pending application Serial Number 649,011, filed February 20, 1946, has an annular front wall 19 made up of relatively large mesh screen, the screen being supported on a plurality of radially extending spokes. These spokes have their outer ends secured to the circumference of the cylinder and have their inner ends secured to a tubular ex-

5 tension member 21 which is of such length and shape, as shown in Figure 2 as to extend through the opening 13 in the panel 12. The panel 12, as shown in Figure 1, has roller members 22 and 23 secured thereto in such position that the tubular member 21 and the cylinder 17 are supported for rotation in a manner described later in more detail, this front support being in addition to the rear support bearing 14 on the rear panel 11.

10 The general arrangement of the dryer as regards the position of the clothes cylinder and air circulating duct is similar to that shown in the aforementioned co-pending application, Serial No. 649,011. For the purpose of circulat- 15 ing air a blower housing 32 which carries a blower impeller 31 is supported on the front panel 12 and exhausts into an air circulating duct 33 also carried on the front panel which circulates air over a heating element 34. An inlet into the 20 duct from the front of the annular shaped wall 19 through the panel 12 is provided which inlet opens into the center of the impeller 31, the inlet being shown at 35 in Figure 2. The outlet from 25 the duct into the machine is back of the heating element 34 shown in Figure 1. The machine is enclosed by panels 42, 43 and 46 and a clothes door opening 47 is provided in the front of the machine in which a glass section 49 is included so that the tumbling of the clothes may be ob- 30 served. The clothes door is mounted in a tubular portion 48 so that a means is provided to remove the clothes from the dryer through the tubular portion 48 and the tubular member 21 which is attached to the drum.

35 The tubular member 21 serves as a pulley for driving the cylinder 17 and serves as well for a central access opening for loading wet clothes into the dryer and to remove the clothes therefrom after drying. A motor 24 provides power 40 for rotation of the cylinder 17 through a belt 25 which drives a large pulley 26 which rotates a smaller pulley 27. The pulley 27 carries a belt 28 which extends around the tubular member 21 and also extends between each of the roller mem- 45 bers 22 and 23 and the tubular member 21. The weight of the cylinder is supported on the rollers 22 and 23 through the belt 28.

As shown in Figure 3 the shape of the rollers 22 and 23 is such that the belt 28 will contact a 50 flat surface thereon and assure a supporting of the load of the tubular member 21 through the belt 28. It is apparent that the provision of a belt between the supporting rollers and the tubular member assures a relatively large arc of frictional contact on the tubular member and also

eliminates the necessity for providing separate contact areas on the tubular member for both the rollers and the belt. Furthermore, the depth of cabinet required to assemble a complete unit is reduced by this arrangement since the supporting rollers and the belt can be in the same plane.

Although the invention has been described by reference to a specific structure found practical in actual operation it is intended that various modifications may be made within the scope of the following claim.

I claim:

In a machine of the character described having a rotatable clothes containing cylinder mounted for rotation on a substantially horizontal axis, a tubular member forming a central front opening concentric with the axis of rotation of said cylinder and extending outwardly from said

cylinder, a driving motor, a belt driving from said motor extending around said tubular member for rotating said cylinder by contact with the outer surface of said tubular member, a pair of rollers contacting said belt and positioned below said tubular member in position to effect a support of said tubular member and said cylinder through said belt.

ALEXANDER L. REITTER.
